US00D876840S

(12) **United States Design Patent** (10) **Patent No.:** **US D876,840 S**
(45) **Date of Patent:** **** Mar. 3, 2020**

(54) **PAINT APPLICATOR**

(71) Applicant: **DESIGNING SOLUTIONS, LLC**,
Silver Spring, MD (US)
(72) Inventor: **Deborah Wiener**, Chestertown, MD
(US)
(73) Assignee: **Designing Solutions, LLC**,
Chestertown, MD (US)

(**) Term: **15 Years**

(21) Appl. No.: **29/686,960**

(22) Filed: **Apr. 9, 2019**

Related U.S. Application Data

(63) Continuation of application No. 29/640,796, filed on Mar. 16, 2018, now Pat. No. Des. 844,998.

(57) **CLAIM**

The ornamental design for a paint applicator, as shown and described.

DESCRIPTION

FIG. 1 is a front perspective view of my design;
FIG. 2 is a front view of the design;
FIG. 3 is a rear view of the design;
FIG. 4 is a left-side view of the design;
FIG. 5 is a right-side view of the design;
FIG. 6 is a top view of the design;
FIG. 7 is a bottom view of the design;
FIG. 8 is an exploded view of the design shown in FIG. 1;
FIG. 9 is a front perspective view of an alternate position of the design shown in FIG. 1;
FIG. 10 is a front perspective view of a second embodiment of my design;
FIG. 11 is a front view of the second embodiment;
FIG. 12 is a rear view of the second embodiment;
FIG. 13 is a left-side view of the second embodiment;
FIG. 14 is a right-side view of the second embodiment;
FIG. 15 is a top view of the second embodiment;
FIG. 16 is a bottom view of the second embodiment;
FIG. 17 is an exploded view of the design shown in FIG. 10; and,
FIG. 18 is a front perspective view of an alternate position of the design shown in FIG. 10.

In the drawings, the evenly spaced dash-dash broken lines are for the purpose of illustrating portions of the paint applicator and form no part of the claimed design. In FIGS. 8 and 17, the dot-dash broken lines are for the purpose of illustrating the order of assembly of the parts shown in the exploded views and form no part of the claimed design.

1 Claim, 12 Drawing Sheets
